CASE FOR SPECTACLES

Cicely D. Cashion, Evanston, Ill.

Application April 29, 1953, Serial No. 24,768

Term of patent 7 years

(Cl. D57—1)

To all whom it may concern:

Be it known that I, Cicely D. Cashion, a citizen of the United States, residing in the city of Evanston, county of Cook, and State of Illinois, have invented a new, original, and ornamental Design for a Case for Spectacles, of which the following is a specification, reference being had to the accompanying drawing, forming a part hereof.

Fig. 1 is a front perspective view of a case for spectacles showing my new design, the rear being plain; and

Fig. 2 is a front elevational view thereof.

I claim:

The ornamental design for a case for spectacles, as shown and described.

CICELY D. CASHION.
